IGNITER

Application filed October 7, 1929. Serial No. 398,037.

- The invention relates to electrical igniters more particularly designed for use in connection with oil burners for automatically igniting the fuel whenever discharged from the burner. It is the object of the invention to obtain a construction which will be operative under varying conditions and particularly where there are fluctuations in the voltage of the electrical current used.
- In the present state of the art electrical igniters have been used in connection with oil burners which are provided first with an electrical heating means for raising the temperature of the oil and second with an igniting means for the oil or its vapor. For the first of these means it is usual to employ a resistor through which an electrical current of normal commercial voltage is passed, the resistance of the resistor being so determined as to produce the desired heating effect at the standard voltage. The second device requires a much higher voltage in that it is necessary to have a jump spark. An objection to such constructions is that the circuit of the two voltages may interfere with each other if too closely associated and if separated the oil vaporized by the resistor may not traverse the path of the spark.
- To overcome the objection just described I have devised a construction of igniter which also has a heat resistor and a jump spark, but without such great difference in electrical potential. As the high potential is required for the jump spark, I have substituted for the low resistance resistor a resistor having a relatively high resistance and in place of passing a low tension current through the resistor I use a current of relatively high voltage. Thus while the heating effect produced by my high resistance resistor is not materially different from that of a low resistance resistor, the difficulties due to interaction of high and low voltage circuits has been overcome.
- One embodiment of my invention is illustrated in the accompanying drawing which shows in perspective a portion of the refractory ring of an oil burning furnace against which the oil spray is directed and in connection with which my improved igniter is
- placed. This drawing also represents diagrammatically the electrical circuit and a transformer used in connection therewith.
- As shown, A is the refractory ring preferably provided with a groove or trough in which the oil from the spray may collect and which extends completely around the ring. B is the heating resistor which may be either embedded in the ring A or placed outside the same but in the path of the fuel spray. This resistor must be of relatively high electrical resistance and I have found that a satisfactory material from which it may be formed is a mixture of granular carbon and refractory particles of an insulator nature with a suitable binder to form a solid mass. The electrodes or terminals C for the resistor are preferably formed of metal and are enclosed in suitable insulator tubes D also of a refractory nature. The ends of the electrodes C are embedded in the body of the resistor B being suitably spaced from each other to obtain the desired electrical resistance in the intermediate body.
- The jump spark igniter is arranged in connection with the resistor B and comprises a metallic electrode E passing through insulator tubes F and extending in proximity with the resistor B at the point of location of one of the electrodes such as C'. The insulator tubes D and F are mounted in any suitable manner upon the ring A as by passing through apertured lugs G formed on said ring.
- For furnishing current of suitable voltage both to the resistor and to the jump spark, a transformer is necessary and preferably a single transformer is used for both currents. Thus as diagrammatically shown, H is the primary coil of the transformer receiving current of a normal voltage such for instance as 110. I represents the magnetic core and J and J' the secondary coils which furnish current at the voltages desired for the two circuits. The coil J delivers the lower voltage such for instance as a difference in potential of approximately 2000 volts between the terminals C and C'. The coil J' which has the common terminal C' delivers current with a difference in potential between this terminal 100

and the terminal E such as to allow a current therethrough of approximately 180 milliamperes while the spark F has a current flow of approximately 18 milliamperes. These voltages and currents are suitable for practical and reliable operation but may be varied within a wide limit by suitable re-design of the resistor element.

With the construction as described whenever the electrical circuit is closed in the primary, current will pass through both secondary circuits. The current traversing the resistor B will raise its temperature to a point where the oil spray impinging thereon will be heated and vaporized while the current which jumps the spark gap will ignite the vapor. It is evident that the jump spark in traversing its gap passes through a zone of rich vapor produced by the heating elements and in addition enters the surface of the resistor upon which the oil spray from the burner impinges. The importance of this direct application of the spark to the spray is very great and results in practical and reliable ignition under conditions where systems of a somewhat similar nature often fail. The igniter is so located in relation to the refractory ring A that the flame will be propagated by the oil in the groove or trough A' and in that manner will ignite the entire supply discharged from the burner.

What I claim as my invention is:

1. An electrical igniter for liquid fuel burners comprising a high resistance refractory resistor on which liquid fuel is deposited, terminals embedded therein, an electrode spaced from said resistor and means for supplying high tension current to both traverse the resistor and to form a jump spark between the same and said electrode.
2. An electrical igniter for liquid fuel burners comprising a high resistance refractory resistor on which liquid fuel is deposited, terminals embedded therein and an electrode spaced from said resistor adjacent to one of the embedded terminals and means for supplying high tension current to traverse the resistor and to form a jump spark, the embedded terminal adjacent to said electrode forming a common terminal for both circuits.
3. An electrical igniter for liquid fuel burners comprising a high resistance refractory resistor on which liquid fuel is deposited, terminals embedded therein, an electrode spaced from said resistor adjacent to one of the embedded terminals, a transformer having two secondary coils having a common terminal connected to said embedded terminal adjacent the said electrode, the other terminals of said secondary coils being connected respectively to said electrode and to the other embedded terminal whereby high tension current is supplied both to the spark cap and for traversing the resistor.
4. In an electrical igniter for liquid fuel

burners, a refractory ring against which the fuel spray is discharged provided with a groove or trough for receiving the accumulating fuel, a high resistance resistor located adjacent to said ring and trough, terminals embedded in said resistor, an electrode spaced from said resistor adjacent to one of said terminals and means for supplying high tension current to both traverse the resistor and to form a jump spark between the same and said electrode whereby the fuel heated by said resistor will be ignited by the spark and the flame will be propagated by the fuel in said trough.

In testimony whereof I affix my signature.

MILTON A. POWERS.
